UNITED STATES PATENT OFFICE.

RALPH MORDIN, OF LONDON, ENGLAND, ASSIGNOR TO THE RELAY AUTOMATIC TELEPHONE COMPANY, LIMITED, OF LONDON, ENGLAND.

AUTOMATIC AND SEMIAUTOMATIC TELEPHONE SYSTEM.

Application filed December 3, 1923, Serial No. 678,234, and in Great Britain January 5, 1923.

My invention relates to multi-exchange systems of automatic or semi-automatic telephony.

It is particularly applicable to systems in which connections are set up over switching apparatus which is under the control, during its switching process, of transistorily used selecting apparatus though some of its features have more general applicability.

10 My invention will be described, for purposes of illustration, in connection with one particular well known system of relay automatic telephone though it is to be understood that it is not to be limited thereto, except to the extent that such limitations may be embodied in the claims.

When connections have to be set up between subscribers in a sub-exchange it is desirable that this be done without tying up junctions to a distant exchange and it is the object of my invention to provide a new and improved arrangement for accomplishing this.

According to my invention I provide connecting apparatus which can be used under the control of a calling line to effect a connection to a line of a group of lines but which when first taken into use will connect the calling line to a line leading to a second connecting apparatus which is, also under the control of the calling line, adapted to effect a connection to or towards a line of a different group of lines the first connecting apparatus being out of control of the calling line unless apparatus associated with the line leading to the second connecting apparatus be controlled in a particular way.

I provide, further, in the first connecting apparatus, means whereby if the said first connecting apparatus is to be prepared for connecting to a line of the first group of lines the line leading to the second connecting apparatus shall be released.

A system somewhat similar to that described above is known in which a line upon becoming a calling line is connected to a connecting apparatus and this connecting apparatus is connected by a line switch to a line leading to a second connecting apparatus. It is undesirable to have to provide for each first connecting apparatus a line

switch. This system has a further disadvantage that it is the inability of the second connecting apparatus to complete a circuit which puts the first connecting apparatus under control of the calling line.

Another system which is somewhat similar is known in which a subscriber's line is connected by a secondary line switch to a connecting apparatus and in which an impulse responding apparatus is associated with the secondary line switch. Both the connecting apparatus and the impulse responding apparatus are operated by some of the impulses representing the wanted number. For local connections the impulse responding apparatus may cause the secondary line switch to release the line leading to the connecting apparatus in order that the said line switch may pick up a line leading to a local connecting apparatus identified by the impulse responder or the impulse responder may cause the release of the line leading to the connecting apparatus and may itself connect the calling line to an appropriate local connecting apparatus.

Any system, however, in which the first connecting apparatus is under directive control of the calling line before apparatus associated with the second connecting apparatus shall have been controlled in a particular way is excluded from our invention.

My invention will now be described with reference to the accompanying drawings of which—

Fig. 1 shows the general trunking scheme; The identity of the various figures with the apparatus shown in Figure 1 is as follows:—

Figure 2 shows a current feeding group, ABF, at the local exchange (KK is the join-line between the two parts of this figure.)

Figures 3, 3^a and 3^b shows a first connecting stage, FSC, at the local exchange; NN is the join-line between Figs. 2 and 3; QQ is the join-line between Figs. 3 and 3^a; UU is the join-line between Figs. 3 and 3^b; ZZ is the join-line between Figs. 2 and 3^a.

Figure 4 shows a repeater REP at the main exchange; VV is the join-line between Figs. 3^a and 4.

Figure 5 shows a first stage main exchange

recorder IRM; YY is the join line between Figs. 4 and 5.

Figure 6 shows a first stage local exchange recorder FIR (or IJR); XX is the join line between Figs. 2 and 6 and WW is the join line between Figs. 6 and 3^b.

The local exchange in Figure 1 may be of any convenient capacity and as represented may be for ten thousand lines (four thousand shown) divided into thousand line groups SE¹, SE², SE³, SE⁴. The trunks leading into groups SE², SE³, SE⁴, are only indicated. The rectangle marked SL represents subscribers' lines which, by means of apparatus of any known sort, become when calling connected to ABF. ABF represent microphone current feeding bridges and control relays which, when taken into use by a calling line extend such calling line through relay switching apparatus FSC, over a junction OJ, to main exchange ME. The junctions OJ terminate at the main exchange in impulse repeaters REP, and are adapted temporarily to take into use impulse responders (known as recorders) IRM to which they will be connected by means of recorder connectors RC. The connection of a subscriber's line by way of ABF, FSC, OJ, REP and RC to a recorder IRM takes place immediately the subscriber removes his receiver. The subscriber then transmits impulses representing the number of the wanted line. The first one or two trains of impulses are received upon IRM and serve to determine whether the call is for a line accessible from ME or for a line accessible from the local exchange. In the former case IRM will control the extension of the connection in the required direction. In the latter case IRM will cause the transmission of an impulse to ABF whereby ABF causes the release of OJ and becomes temporarily associated with a recorder FIR at the local exchange. For a local call, the next train of impulses will be received on FIR which will determine for which of the groups SE the call is destined and will control FSC in such a manner that ABF will be connected to one of the trunks T, say t¹ assuming that the call is for a line in group SE¹. t¹ will become temporarily connected with a final recorder F2R upon which the final trains of digits will be received and which will control the further extension of the connection to a line in group SL.

Calls from the main exchange to the local exchange will come in on incoming junctions IJ with which a recorder IJR becomes temporarily associated. IJR receives a train of impulses to determine into which group SE to extend the connection. The connection will be completed in the same manner as is a local connection.

In connection with Figure 1 it should be understood that each line represents a num-

ber of lines and each ABF, etc. represents a number of those apparatus.

It should, of course, be understood that there would be a number of outgoing trunks OT, Figure 3 and there may, indeed, be a number of groups of such trunks. Further there would be a number of groups of junctions or trunks similar to t¹, Figure 3, depending upon the number of thousand line groups comprising the local exchange. If all these groups be situated at one office the trunks would extend to apparatus similar to that shown in Figure 3^b whereas if they were in separate offices the junctions would extend to apparatus similar to that shown in Figure 3^a.

It may be pointed out here that the only difference between the apparatus shown in Figures 3^a and 3^b is that that shown in Figure 3^a leads over a two wire junction to a repeater (Fig. 4) which is adapted to pick up a recorder whereas that shown in Figure 3^b is adapted, itself, to pick up a recorder.

I will now describe in detail with the aid of the circuit diagrams how the above outlined connection is effected.

It is the usual practice in large automatic telephone systems to have letters as well as figures printed on the dial in order that a big number may be more readily remembered. The letters usually represent the exchange selecting digits.

For the purpose of this example it will be assumed that the local exchange is represented by BX and that the line required is designated by the number 2432. The letters may correspond to any digit and will be taken to correspond to 2 and 9 respectively. Thus the actual number of impulses in each train will be 2—9—2—4—3—2.

When the calling subscriber lifts his receiver to initiate a call, his line is extended in a well known manner to a current feeding group ABF Fig. 2 and a circuit 2 is closed through relay I² over the subscriber's line to negative point a at the bottom break contact of relay ICO. By the operation of I² circuit 3 is closed through a retarded releasing guard relay G.

G closes circuit 4 for relay GX which in turn closes circuit 5 from negative point b through relay BB which energizes.

GX at the same time closes circuit 6 from negative point c through relay MX¹ which energizes. MX¹ closes circuits 7 and 8 putting battery on the outgoing trunk marking relay OTM Fig. 3 and junction marking relay JM Fig. 3^a respectively.

JM is energized because one of the junctions of group A is to be used.

OTM closes circuit 9 from earth point d through the outgoing link marking relay OLM¹.

The combined operation of OTM, OLM¹ and JM Fig. 3^a completes circuit 10 from

earth point *d* to negative point *e* for relay GS which operates and closes a holding circuit for itself and circuit 11 for relay SS.

SS operates and completes circuit 12 from negative point *e* to earth point *d* for outgoing junction marking relay OJM. This energizes and closes a holding circuit over contact *f* and circuit 13 containing OJC and OLC. These relays operate and connect the outgoing trunk OT over outgoing link OLB to the selected outgoing junction OJ1.

OJC and OLC also complete holding circuit 14 from negative point *c* Fig. 2 through MX², OLC, OLB, OJC and OJB.

MX², OLB and OJB energize in this circuit. MX² breaks circuit 6 causing MX¹ to de-energize and thus break circuits 7 and 8 so that OTM and JM de-energize. The operation of OLB marks the outgoing link as busy by opening circuit 9 and the operation of OJB marks the outgoing junction as busy by opening circuit 10. The release of OTM broke the circuit of OJM. The release of OJM breaks the circuit of GS which in turn causes SS to de-energize. Thus the only relays in the connecting apparatus now in an operated condition are those which are held over circuit 14.

The calling subscriber's line is thus extended to the repeater in the main exchange.

To save confusion in reading the circuits in Figures 2 and 4 these two figures may be placed side by side without Figures 3 and 3^a between; further, relays bearing the same reference letters in Fig. 4 as are borne by relays in Fig. 2 will be followed by the numeral (4), thus I (4).

The connection of the A and B feed (ABF or Fig. 2) to the repeater (Figure 4) will 40 result in the completion of circuit 15 from negative point *g* relay I (2) through the two windings of IS in parallel and through the winding of I (4).

I (4) closes circuit 16 in which G (4) 45 operates. This relay does not respond to the impulses which shall be repeated by I (2) to I (4).

G (4) closes circuits 17 and 18 the former from negative point *i* and the latter from 50 earth point *h*. In circuit 17 relay FI Fig. 5 operates and in circuit 18 relay BB (4) operates.

FI in operating completes circuit 19 through RC¹ and P Figure 5.

55 P, the recorder preparing relay, in operating puts battery upon the main battery wire, shown as a heavy broken line. All the BK relays of the impulse counting train will energize in parallel over circuit 20 derived from this main negative wire.

P putting on negative to the main battery feed, hereinafter referred to as P negative, also causes RSR² and RSR¹ to energize over circuit 23.

60 The manner in which a recorder such as

that shown in Figure 5 operates is so well known that a detailed description of the circuit operations is thought to be unnecessary. It is sufficient to state that when impulses corresponding to "B" have been received circuit 28 from P negative at DC¹ will be completed to operate ST.

Impulses for letter "X" are then received by the recorder. This results in THD⁹ being operated in circuit 29 from P negative at DC¹. The operation of THD⁹ completes circuit 31 in which JR operates. Circuit 31 was completed by MC which when it operated put a short circuit on RSR¹ which releases after a slight delay. The release of RSR¹ causes the release of RSR² after a further delay. RSR² controls the release of the recorder but before it can bring about that release the following operations take place. JR being operated leaves earth on the A wire of the recorder and removes it from the B wire.

This condition upsets the balance of IS (4) so that that relay will now operate and close circuit 32 for ICO (4) to operate.

The repeater has now to give this same condition, that is earth on the A wire and nothing on the B wire, to the current feeding group Fig. 2.

ICO (4) in operating closes circuit 33 from earth point *k* Fig. 5 for S¹ (4) which operates and in turn closes circuit 34 for RS¹ (4). (Note the recorder should not have been released by the operation RSR² until circuit 33 was completed).

RS¹ (4) operates and closes circuit 35 which places earth upon the A wire through RS² (4).

RS² (4) in operating closes holding circuit 34¹ for RS¹ (4) so that RS² (4) is now independent of S¹ (4) and ICO (4).

The condition is now that there is earth on the A wire (Fig. 2) and nothing on the B wire because this latter wire is open at contact RSC of RS¹ (4).

Referring to Fig. 2, IS therein will now be unbalanced and consequently will energize over circuit 35. IS closes circuit 36 over which ICO energizes and breaks circuit 35 of IS which de-energizes. ICO now holds over its own contacts. S¹ now has a circuit 37 over which to operate and thus closes circuit 38 for RR which operates and holds over circuit 38¹. At the same time ICO broke circuit 5 of BB which released. The release of BB is timed so that RR has time to operate first.

As soon as RR energizes and BB de-energizes JR¹ will operate over circuit 39 and complete a circuit over its contacts for JR² which operates and holds over circuit 40.

When JR¹ operated it opened circuit 5 and RR and ICO released. RR breaks circuit 39 so that JR¹ de-energizes.

ICO by re-establishing circuit 2 brings

about the re-energization of I and by re-establishing circuit 5 the re-energization of BB and by breaking circuit 35 brings about the release of IS.

5 The calling subscriber's line will now be connected to the local recorder in a manner to be explained.

JR² energizing breaks holding circuit 14 so that all the connecting relays in this circuit will be released.

10 MX² remains energized over circuit 6 so that MX¹ cannot energize again.

15 A circuit 41 was completed by the energization of JR² which may be traced from battery in the current feeding group Fig. 2 over make contacts of GX to earth point l in the recorder connector Fig. 6 through FI. The first stage (i. e. the thousands) recorder at the local exchange is prepared and taken 20 into use in an exactly similar method to that already explained in connection with the recorder at the main exchange.

25 The calling subscriber now dials thousands digit "two" into this local recorder.

30 The recorder operates in the well known manner and when set for digit 2 operates THM². The operation of THM² completes circuit 60 in which is JML Figure 3^b.

35 Figure 3^b, is a trunk (such as t' Figure 1) leading into the same thousand group as is the calling subscriber. Connection to it from the A and B feed (Figure 2) is effected in the same way as was connection to the junction (Figure 3^a). This, it is thought, is sufficiently well understood to render unnecessary a redescription of the operations.

40 When ISB operates in the holding circuit it completes circuit 70 to pick up a final three digit recorder which, in response to the last three figures of the number, brings about a connection between t' and the wanted line in a manner well known in the art.

45 It should here be stated that the repeater (Figure 4) at the main exchange would be capable under certain circumstances of extending a connection to a particular thousands group in that exchange over apparatus similar to that shown in Figures 3 and 3^b.

50 Lines in the main exchange would be represented by "B" and four figures. Thus if the calling subscriber on the local exchange had, instead of dialling BX2432, dialled B2432 the operations would have been as follows:—

55 Referring to Figure 5, the dialling of "B" would have caused the operation of ST and the dialling of 2 would have brought about the operation of THD². This would have completed circuit 50 which would extend to a relay similar to JML Fig. 3^b, but situated at the main exchange and controlling apparatus there.

60 Further, the repeater at the main ex-

change would be capable under other circumstances of completing connections to local exchanges other than that in which the calling line is situated over apparatus similar to that shown in Figures 3 and 3^a.

70 Lines in these other local exchanges would be represented by "B" followed by some letter other than "X" (say M) followed by say a four figure number. Thus, if the calling subscriber on the local exchange had, instead of dialling BX2432, dialled BM2432 the operations would have been as follows:—

75 Referring to Figure 5, the dialling of "B" would have caused the operation of ST and the dialling of M would have caused the operation of, say, THD⁸. This would have completed a circuit similar to 50 but operating upon a relay similar to JML Fig. 3^a situated at the main exchange and controlling apparatus there which gives access to 80 a local exchange other than that represented by BX.

85 The main exchange may be one of several main exchanges in which each main exchange would be represented by a different first letter. For instance a second main exchange may be represented by the letter "M."

90 It has been shown above that the receipt by the main exchange recorder, of impulses 95 for first letter "B" brought about the operation of ST. Now the receipt, by that recorder, of impulses other than for "B" as a first letter, would bring about the operation of one of the relays MX say MX³ for 100 first letter "M." The recorder would then mark out on circuit 51 to apparatus similar to that shown in Figure 3^a but situated at the main exchange. The recorder can have been set for "M" either by a subscriber on main exchange B or by a subscriber on a local exchange in group B.

105 The apparatus similar to that shown in Fig. 3^a at exchange B would be the outgoing end of a junction leading to main exchange 110 "M" at which exchange it would terminate in a repeater similar to that shown in Figure 4.

110 The repeater at exchange "M" would pick up a recorder similar to that shown in Figure 5 and since the call is destined for exchange M or for one of its local exchanges ST at exchange M must be operated. The operation of ST can be effected in any well known manner, as, for instance, by the dialling of an additional impulse.

115 What I claim is:—

120 1. An automatic telephone system in which lines are selected by calling an invariable numerical designation comprising a 125 main exchange, a number of lines thereon, a local exchange, a number of lines on the local exchange, a two-wire only junction between the exchanges, apparatus at the local exchange which upon any line thereon be-

coming a calling line will operate at once to extend this line to the junction, and means located in the main exchange and adapted upon being controlled by the calling subscriber in a particular manner so to modify the conditions of the said apparatus as to cause said apparatus to release the junction.

5 2. An automatic telephone system comprising a main exchange, a local exchange, two-wire only junctions connecting the exchanges, apparatus in the local exchange adapted to connect any calling line in the local exchange to an idle one of said junctions and means associated with the main exchange end of the selected junction for sending back an impulse to said apparatus should the call be a local one, so that said apparatus will release the junction.

20 3. A telephone system in which lines are selected by calling an invariable numerical designation comprising a local exchange, a main exchange, a two-wire only junction from the local exchange to the main exchange, a number of lines on the local exchange, a number of lines on the main exchange, apparatus at the local exchange for connecting a calling line of the local exchange to the junction to the main exchange, means at the main exchange adapted to 25 bring about under the control of the calling subscriber the connection of the junction to a wanted line in the main exchange or to permit the release of the junction, and apparatus at the local exchange adapted on the junction being thus released to be controlled by the calling subscriber to bring about connection of his line to another line on the local exchange.

40 4. A telephone system comprising two local exchanges, a main exchange and a junction from each local exchange to the main exchange, a number of lines on each local exchange of which some are junctions to the other local exchange, a number of lines on the main exchange, apparatus at each of the local exchanges for connecting a calling line of that local exchange to the junction to the main exchange, apparatus at the main exchange adapted to bring about under the control of the local subscriber the connection of the junction to any line in the main exchange or to permit the release of the junction to the main exchange and apparatus at each local exchange adapted on 45 such release of the junction to be controlled by the local subscriber and to bring about

connection of the calling line to another line on the same local exchange whether such line be the line of a subscriber on the same local exchange as the caller or a junction 60 to the other local exchange.

5. A telephone system comprising a main exchange, a number of lines thereon, a local exchange, a number of lines thereon, two-wire junctions connecting the exchanges, 65 current feeding apparatus and switching apparatus at the local exchange adapted on one of the lines on the local exchange becoming a calling line to connect that line to an idle junction, impulse repeaters located at the main exchange and associated with the junctions, an impulse responder adapted to be actuated by the repeaters and to extend the call to a line on the main exchange or to transmit an impulse back to the feeding and 70 switching apparatus at the local exchange, whereby such apparatus releases the junction and an impulse responder at the local exchange adapted on the release of the junction to extend the calling line to one of the 75 lines on the local exchange.

6. A telephone system comprising two local exchanges, a main exchange and a junction from each local exchange to the main exchange, a number of lines on each local exchange of which some are junctions to the other local exchange, a number of lines on the main exchange, current feeding apparatus and switching apparatus at each local exchange adapted on one of the lines 80 of a local exchange becoming a calling line to connect that line to an idle junction to the main exchange, impulse repeaters located at the main exchange and associated with the junctions connecting the local exchanges to the main exchange, an impulse responder adapted to be actuated by the repeaters and to extend the call to a line on the main exchange or to transmit an impulse 85 back to the feeding and switching apparatus at the local exchange, whereby such apparatus releases the junction and an impulse responder at the local exchange adapted on the release of the junction to extend the calling line to one of the lines of the same local 90 exchange or over a junction to the other local exchange.

100 In testimony that I claim the foregoing as my invention I have signed my name this 28th day of September, 1923.

105 RALPH MORDIN.
